UNITED STATES PATENT OFFICE.

BENJAMIN F. COFFMAN, OF DECATUR, ILLINOIS.

INTERNAL-COMBUSTION ENGINE.

1,354,535.

Specification of Letters Patent.

Patented Oct. 5, 1920.

Application filed October 18, 1919. Serial No. 331,662.

To all whom it may concern:

Be it known that I, BENJAMIN F. COFFMAN, a citizen of the United States, residing at Decatur, in the county of Macon and State of Illinois, have invented certain new and useful Improvements in Internal-Combustion Engines, of which the following is a specification.

This invention relates to engines.

10 It relates particularly to internal combustion engines, although not limited exclusively to engines of this type.

An object of the invention is to provide 15 an improved engine which is completely inclosed.

Another object is to provide an engine having a high torque for a given length of stroke.

Another object is to provide an engine 20 having a high starting torque.

Another object is to provide an improved engine of compact construction.

Other objects and advantages will appear 25 from the description and claims.

20 In the drawings: Figure 1 is a central section through the engine.

Fig. 2 is an end elevation with the in- 25 closing plate removed.

Fig. 3 is a transverse section taken on 30 line 3—3 of Fig. 1.

Fig. 4 is an enlarged section taken on line 4—4 of Fig. 1.

Fig. 5 is a transverse section taken on line 5—5 of Fig. 4.

15 In the embodiment of the invention chosen for illustration, eight cylinders of the internal combustion engine, air cooled type, are symmetrically grouped about the engine fly wheel.

0 The cylinders are arranged in pairs with one on each side of the fly wheel, and their pistons are connected, by suitable

gearing, directly to the fly wheel. The symmetrically grouped cylinders, and all of the working parts of the engine are inclosed

5 in a housing which serves to protect the engine and the attendants.

The engine, as illustrated in the accompanying drawings, comprises a substantially cylindrical supporting frame 5, having a base 6, upon which the engine stands.

Passing through the axis of the frame 5 is the main power shaft 7, to which is keyed the engine fly wheel 8. The engine cylinders 9 are arranged in pairs symmetrically about the shaft, the two cylinders, one on each side of the fly wheel, are supported by and between a pair of annular plates 10 and 11, to which the cylinders are connected.

Cross beams 12 extend between the plates 10 and 11, and sufficiently space them apart 60 and serve as means for supporting the walking beam 13, one for each pair of cylinders, which are pivoted to the bracket 14 on the cross beam, as at 15. The outer ends of the walking beams carry links 16, which are pivoted thereto, as at 17, and which are connected to the pistons 18, within the cylinders 9, as at 19. An inner hub portion 20, to which the plates 10 are attached, as at 21, is provided with flat annular plates 22, upon 65 the outer edge of which are supported a series of gear wheels 23. These wheels mesh with the inner gear 24 of the fly wheel 8, and are rotatably supported on the short shafts 25. A wrist pin 26 is placed on one 70 side of the axis of the shaft 25, of the gear wheel 23, and supports a link 27, that is connected to the wrist pin by a universal joint bearing 28, more clearly shown in Fig. 3. The link 27 is provided with arms 29 80 that are pivotally connected to the oval-bearing sleeve 30, so that the link may have some free movement with respect to the wrist pin 26, in the operation of the device. The upper end of the link 27 is connected 85 to the walking beam 13, as at 31, by a shackle 32, which is connected to the link by a pin, as at 33; so that the link may have some lateral movement with respect to the walking beam.

90 A cam shaft 34 finds bearing in the plate 10 and is a part of the crank 26, being connected thereto by a part 35. The shaft 34 carries a geared pinion 37, meshing into a gear wheel 38, in a two to one relation. The 95 gear wheel 38 is mounted on a shaft 39. This is the cam shaft for operating the valves 40 and 41 of the engine.

The cam shaft carries the cam 42 for operating the valve 40, and another cam 43 for 100

operating the exhaust inlet valve 41. One of these valves is the intake valve and the other is the exhaust valve. Bearing on the cam 42 is a roller 44, carried in a bifurcated arm 45, that has a sliding bearing in the block 46 secured to the plate 10, the upper end of which is connected to a lever 47, as at 48; the lever is pivoted to an arm 49 of the frame, as at 50, and its opposite free end is down curved, as at 51, and bears upon the top 52 of the valve stem 53. A spring 54 normally holds the valve 40 closed but the cam 42 will open the valve at the proper time against the resilient opposition of the spring 54. The other, or exhaust valve, of each engine is provided with a similar means, that is to say the valve 41 is operated by the cam 43, by the pressure of the roller 55 thereon, which is secured to the bifurcated arm 56, of the rod 57. The rod is slidingly supported in the block 58 that is secured to the plate 10, and on its outer end, as at 59, is pivoted to a lever 60, which is pivoted to the arm 61, as at 62. The incurved end 63 of the arm 60 bears upon the upper end 64 of the valve stem 65, and the valve 41 is normally held closed by the spring 66. The valve operating mechanism of each of the engines, grouped around the fly wheel, answers the foregoing description. The intake pipe 67, controlled by the valve 40, leads to the proper source of fuel supply, and the outlet, or exhaust pipe 68, leads to a suitable remote point for discharging the burnt gases or combustion.

Now it is manifest, from the foregoing description, that when the shaft 39 is rotated by the gear wheel 38, and its co-acting pinion 37, that the revolutions of the shaft 39 will be one-half the number of revolutions in a given time of the main shaft 7, and therefore when the cams 42 and 43 are properly adjusted the valves 40 and 41 will be operated thereby, in proper cyclic timed relation.

Each cylinder is furnished with a spark plug 70, energized by wire 71, coming from a suitable source of electric supply.

Plates 72 are used to cover the end openings in the plates 11, and may be secured thereto by screws 73.

A cylindrical portion 74 may surround the plates 10 and 11 and be secured thereto by screws 75.

From the foregoing description the operation of the engine will be readily understood, by persons skilled in the art.

While I have herein shown a single embodiment of the invention for the purposes of disclosure, it is apparent that changes in the configuration and disposition of the parts may be made within the scope of the appended claims.

Having described the invention, what I claim as new and desire to secure by Letters Patent is:—

1. A device of the character described having in combinative association, a power shaft; a geared fly wheel mounted thereon; a plurality of engines on each side of the fly wheel; pinions geared to the fly wheel; means to connect engines on opposite sides in pairs, said connecting means also connected to said pinions to drive the fly wheel. 75

2. An engine having in combinative association, a cylinder; a piston, a shaft, a fly wheel mounted thereon, and a stationary walking beam adapted to transmit the power of the piston directly to the rim of the fly wheel and through the wheel to the shaft upon which it is supported. 80

3. An engine having in combinative association, a pair of cylinders; and pistons and a fly wheel between the pairs of cylinders, 85 said fly wheel having an internal gear on the inner surface of its rim; a pinion meshing therewith, and connections between the pinion and both pistons whereby to rotate the fly wheel. 90

4. An engine having in combinative association a power shaft; a fly wheel, mounted thereon, and having an internal gear on each side; a pair of engines, one on each side of the fly wheel; a pinion meshing with each 95 internal gear; connection between the respective pinion to rotate the fly wheel, and a walking beam connecting the pistons of the pair of engines and connected to said pinions. 100

5. A device of the character described, having in combinative association a power shaft; a fly wheel mounted on the shaft, and having a gear part near its periphery on each side of the wheel; a shaft bearing, on each side of the fly wheel, two annular plates secured to the respective bearings; a plurality of internal combustion engines, located in pairs, and supported on said plates; a pinion for each engine, connected to the piston thereof and in mesh with the respective gear of the fly wheel, and a walking beam, connecting the pinions and opposite engines in pairs, and supported by the plates. 110

6. A device of the character described, 115 having in combinative association a power shaft; a fly wheel mounted on the shaft; and having a gear part near its periphery; a pair of plates, spaced apart and diametrically parallel with the fly wheel; an engine 120 supported on said plates; a pinion in mesh with the gear of the fly wheel, and connected to the piston of the engine, whereby the reciprocation of the piston rotates the fly wheel through the pinion, and a cam shaft 125 supported on said plates and rotated by the shaft upon which the pinion is supported.

7. A device of the character described,

having in combinative association a power shaft; a fly wheel, having a gear near its periphery on each side thereof and mounted on said shaft; a pair of parallel annular 5 plates on each side of the wheel; a plurality of internal combustion engines, spaced apart around the axis of said pairs of plates and supported thereon; a pinion connected to the respective piston, of each engine, and to

the gear of the fly wheel, and a walking beam for each pair of engines, connecting the engine and pinion on one side of the fly wheel to the engine and pinion on the other side of the fly wheel in coöperating pairs.

In testimony whereof I hereunto subscribe my name.

BENJAMIN F. COFFMAN.
